United States Patent Office.

BERNARD SMITH, OF CINCINNATI, OHIO, ASSIGNOR TO AMERICAN BURIAL CASE COMPANY, OF SAME PLACE.

Design No. 2,668, dated June 4, 1867.

CASE A.

DESIGN FOR A BURIAL CASE.

The Schedule referred to in these Letters Patent and making part of the same.

TO WHOM IT MAY CONCERN:

Be it known that I, BERNARD SMITH, of Cincinnati, in the county of Hamilton, and State of Ohio, have invented a new Design for Burial Cases, which design is represented in the accompanying photograph making part of this specification.

I claim, and desire to secure by Letters Patent—

The design for burial cases, substantially as represented in the accompanying photograph.

In testimony of which invention I hereunto set my hand.

BERNARD SMITH.
